BRASSIÈRE

Abraham L. Finkelstein, New York, N. Y., assignor to Snug-Fit Foundations Inc., New York, N. Y., a corporation of New York

Application August 15, 1939, Serial No. 290,183

3 Claims. (Cl. 2—42)

This invention relates to a brassière and to foundations and other garments having a brassière element incorporated therein.

It is an object of this invention to provide a garment of the character described which will firmly support the breasts and which will give them form and position, disposing of surplus tissue where it will be least conspicuous and to do so without inconvenience or discomfort.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description, taken in connection with the accompanying drawing, in which there is shown a brassière embodying this invention.

As shown therein the brassière is made up of two front pieces 10 and two back pieces 11. The front piece being attached together by a central seam 12 and each being attached to corresponding back pieces 11 by a side seam 13. The back pieces are provided with the customary fastening means 14 for attaching the two together at the back.

To get a firm support for the breasts the garment is preferably made of a light but firm material.

Each front piece 10 is shaped to the contour desired for the breasts as, for example, by seams 15 converging toward the central point 16 between the breasts and by a vertical seam 17. These front pieces thus form breast pockets preferably having a central point 18 to receive the nipple and the seam 17 extends vertically downwardly from the point 18 to the lower edge of the garment.

Each of the pieces 10 has its upper edge inclined upwardly toward a point 19 above the nipple point 18.

In accordance with this invention there is provided a tape or ribbon 20 extending upwardly from a point 21 in the side seam to the point 19 and a tape 22 extends downwardly from the point 19 through the point 16 to a point 23 beneath the other breast and substantially in line with the base circle of the breast pocket. A shoulder strap 24 is attached at one end to the top of the member 10 at 10a and to the point 19 and has its other end attached to the back portion 11 as shown at 25. This point being preferably ad-

jacent to but spaced from the center of the back.

With this construction the strain imposed on the garment by the shoulder strap is in part carried by the tape 20 which lies above and on the outside of the breast pocket and in part by the tape 22 which distributes the strain to the point 23.

With this construction the strain at the point 23 is distributed through the fabric of the garment below the breast tending to create a more or less defined lower edge of the formed portion of the breast but without any sharp line of cut off which might cause discomfort or injure the breast. In part the shape of the breast and the well defined character of its lower edge is determined by the location of the point 23 since at the point 23 the strain of the shoulder strap is concentrated but from that point to the point 21 the strain is distributed through the fabric.

This arrangement causes the fabric to assume an intermediate line of division between the point 23 and 21 which determines that portion of the breast which shall be held in its molded form and uplifted or supported by the garment and that portion which is allowed to remain flat against the chest below the molded portion.

In order to more definitely concentrate the strains imposed by the shoulder strap to the lower side of the breast the garment is provided with an inner lining 26 defined by the characters a, b, c, d, e, f, and g and the inner lining and the garment itself are attached together by lines of stitching 26 which, in general, converge from the center line of the lower portion of the breast pocket to the side seam and to the central seam, thus forming a diamond shaped reinforcement of the lower side of the breast pocket giving firmer support to the breast and more carefully distributing the strain without discomfort.

It will also be seen that in the form shown the tape 22 is bent downwardly as shown at h, then downwardly and inwardly as shown at i and across the bottom as shown at k and then upwardly by similar bends at m, n and p to join with the tape 22 on the opposite side. This not only furnishes a simple system of making the tapes continuous but, what is more important, it helps distribute the pull by resiliently balancing the lateral strains on one side of the center line against those on the other side.

With a garment of this kind each breast is in part supported from its own shoulder strap but it is in part supported by the shoulder strap on the opposite side and this assists greatly in maintaining the form of the breast and in

preventing the surplus tissue from spreading to the side underneath the arms.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desired to secure by Letters Patent, is:

1. A brassière comprising a body encircling member having breast contour-defining breast pockets and vertical seams at the outer edges of said breast pockets, shoulder straps connected to said body encircling element at a point above said breast pockets, a reinforcing strip having a strain taking portion extending downwardly from said point through a point midway between the breasts to a point on the opposite side of the vertical center line and below said midway point

and said strain taking portion there terminating, said strip being connected to the body encircling element from the top of the shoulder to the termination of said strain taking portion of said strip, whereby each breast pocket is supported diagonally upwardly toward the shoulder strap on the opposite side by said strip and whereby the breast tissue is maintained in form by said pocket and is held upwardly and forwardly thereby and is held distinct from the adjacent breast by the strain taking portion of said reinforcing strip.

2. A device in accordance with claim 1 having a second reinforcing strip extending from said shoulder strap diagonally downwardly toward the outer side of the breast and attached to the body encircling element substantially at the outer edge of the breast pocket.

3. A device in accordance with claim 1 having 20 a second reinforcing strip extending from said shoulder strap diagonally downwardly toward the outer side of the breast and attached to the body encircling element substantially at the outer edge of the breast pocket, the lower side 25 of each of said breast pockets being reinforced from the termination of the strain taking portion of said first mentioned reinforcing strip to the side seam.

ABRAHAM L. FINKELSTEIN.
